UNITED STATES PATENT OFFICE

2,453,632

CRUTCH

Anders R. Lofstrand, Jr., Silver Spring, Md.

Application October 15, 1945, Serial No. 622,338

3 Claims. (Cl. 135—50)

1

This invention relates to crutches and more particularly to crutches of the adjustable length type.

An object of this invention is to provide a crutch adjustable as to length which is made out of telescoping tubular members and which includes an arm grip sleeve pivotally secured to the upper end of the support whereby the user may release the hand grip and still retain the support on the arm.

Another object of this invention is to provide a crutch of this kind embodying a split sleeve adapted to grip the arm and a right angularly disposed hand grip below the arm sleeve, the arm sleeve being pivotally secured at the upper end of the support so that the crutch will be detachably secured to the arm and the hand grip can be used during walking and released when the user is stationary.

A further object of this invention is to provide a crutch of this kind including readily adjustable means whereby the length of the crutch support can be adjusted, and if desired the crutch can be disassembled so that it will occupy only a small space.

With the foregoing objects in view and others which may hereinafter more fully appear, the invention consists of the novel construction, combination and arrangement of parts, as will be more specifically described, and illustrated in the accompanying drawings, wherein are shown embodiments of the invention, but it is to be understood that changes, variations and modifications may be resorted to which fall within the scope of the invention, as claimed.

Figure 1 is a detail front elevation of a crutch partly broken away constructed according to an embodiment of this invention.

Figure 2 is a detail side elevation partly broken away of the device.

Figure 3 is an enlarged fragmentary sectional view of the upper portion of the lower support,

Figure 4 is a fragmentary vertical section of the lower end of the inner support,

Figure 5 is a fragmentary side elevation of the upper end of the crutch with the sleeve or arm clamp in a substantially horizontal position.

Referring to the drawings, the numeral 10 designates generally an outer tubular member and the numeral 11 designates generally an inner lengthwise adjustable tubular member. The outer tubular member 10 has extending from the upper end thereof an elongated supporting bar 12 which is formed with an obtusely extending upper portion 13. The lower end of the supporting bar 12

is formed with a reduced stud 14 having a downwardly opening socket 15 in the lower end thereof and a releasable securing means generally designated as 16 secures the stud 14 to the upper portion of the outer member 10. The securing means 16 includes a substantially U-shaped spring 17 which has secured to the upper end portions thereof a pair of plugs 18 which are adapted to slidably engage through openings 19 formed in the socket 15 and openings 20 formed in the tubular member 10.

The support 12 has extending right angularly from the lower portion thereof a hand grip member 21 having an annular rib 22 at its outer end and formed with finger notches 23 in the lower side thereof. The bar 12 with the extension 13 is substantially T-shaped in transverse section and has formed in the upper end thereof a pair of ears 23 within which a pivot bar 24 is adapted to loosely engage.

The bar 24 is pivotally mounted on a pivot 25 extending between the ears 23. An arm clamping sleeve 26 is secured by fastening members 27 to the pivot bar 24 and the sleeve 26 is split at its forward side as indicated at 28, and the ends of the sleeve are then rolled back as indicated at 29. The upper and lower edges of the sleeve 26 are also flared outwardly as indicated at 30 and 31 respectively.

30 The inner tubular member 11 is adjusted lengthwise of the outer tubular member 10 by means of a pair of spring pressed plugs 32 which are carried by the free ends of a U-shaped spring 13. A cylindrical reinforcing member 34 is 35 welded or otherwise firmly secured within the inner member 11 and provides a reinforcing means for the inner member 11 adjacent the locking plugs 32. The plugs 32 are slidable in registering openings 35 and 36 which are formed in the reinforcing member 34 and the inner member 11 respectively.

40 A lower plug 37 is disposed in the lower end of the inner member 11, being secured therein by a pair of diametrically disposed fastening members 38. The plug 37 is formed at its lower end with an annular flange 39 engaging against the lower end of the inner member 11. A cushion member 40 engages about the lower end of the inner member 11 and includes a cylindrical side wall 41 having formed integral therewith a lower wall 42 and preferably an annular rib 43 is formed at the lower end of the cushion member 40. The cushion member 40 may be made out of rubber or other cushioning material which will not

3

readily wear upon contact with rough surfaces or the like.

In the use of the crutch the arm may be extended through the sleeve 26 and the grip member 20 grasped in one hand. The inner and outer members 10 and 11 are adjusted as to length by pressing the plugs 32 inwardly and then moving the inner member 11 either inwardly or outwardly until the plug 32 registers with a selected pair of openings 44 in the outer member 10. In the event it is desired to release the hand grip 20 without taking the arm gripping member 26 from the arm and to provide for lighting a cigarette or for other purposes, the arm engaged with the sleeve 26 may be raised, the sleeve swinging from the pivot 25.

If it is desired to collapse the crutch, the upper supporting bar 12 may be removed from the sleeve or tubular member 10 by pressing the buttons or plugs 18 inwardly and then pulling the bar 12 from the tubular member 10. The inner tubular member 11 may be moved inwardly to the limit permitted by the cushion member 40 or may be completely withdrawn from the outer member 10 by pushing the buttons or plugs 32 inwardly and then shifting the inner member 11 endwise in the desired direction.

With a crutch as hereinbefore described the crutch may be made out of lightweight metal which will have sufficient strength to provide the necessary support and still be of sufficiently light weight that it will not be heavy to use.

What I claim is:

duced stud on the lower end of said bar engaging in the upper end of the outer of said tubular members, locking pins engaging through said stud and said outer member, said outer member formed with a longitudinal series of transversely aligned openings therein, locking pins engaging through the upper end of the inner of said tubular members and in selected openings of said outer tubular member securing said members in selected adjusted position, an obtusely disposed upper portion on said supporting bar, and a split arm supporting sleeve rockably carried by said upper portion of said bar.

2. A crutch as set forth in claim 1, including a forwardly extending handle on said bar below said split sleeve.

3. A crutch as set forth in claim 1, including U-shaped springs in said supporting member, the free ends of the arms of said springs being fixed to the inner ends of said locking pins.

ANDERS R. LOFSTRAND, JR.
